UNITED STATES PATENT OFFICE

2,001,308

SHOE SEWING MACHINE

Otto F. Hoppe, Frankfort-on-the-Main, Germany, assignor to United Shoe Machinery Corporation, Paterson, N. J., a corporation of New Jersey

Application September 20, 1933, Serial No. 690,207
In Great Britain October 12, 1932

4 Claims. (Cl. 112—60)

This invention is concerned with the manufacture of footwear and sewing machines suitable for use therefor and has reference particularly, though by no means exclusively, to methods of and means for producing an article of footwear simulating in appearance and having the qualities of the so-called Sahara sandal, while obviating the thonging together, by a lace or thong, of the upper and sole, which is the characteristic of that sandal and which has, up to the present at all events, perforce been a hand operation and therefore slow and generally objectionable to footwear manufacturers.

The present invention, amongst other things, makes provision for sewing together by machine (a) an outwardly directed flange moulded, preferably substantially parallel to the margin of the sole tread, on the periphery of the usual upstanding rim of a Sahara sandal type of sole and (b) an upper which has had provided on it, a marginal bead of substantial (say one quarter of an inch) diameter, the sewing that unites these parts being concealed (more or less) in the crease between the bead and the upper so that as the result of this machine sewing operation a shoe unit is produced which may be finished by trimming off excess flange and then giving a rounded form to the residual flange portion, as by curling that portion back towards the rim over the stitching on the treadward face of the shoe. The result above aimed at may be secured, in accordance with the present invention, by the employment of a curved hooked needle boot or shoe outsole stitching machine of conventional type by modifications thereof of the character hereinafter described by way of example.

In the accompanying drawings:

Figure 1 is a right hand side elevational view of portions of a machine of the general nature of that disclosed in U. S. Letters Patent to French and Meyer, No. 473,870 dated April 26, 1892, but equipped with novel parts to enable it to perform the sewing of an outwardly directed flange moulded on the periphery of the rim of a Sahara sandal type of sole to a beaded upper;

Figure 2 is a front elevational view of certain of the sewing instrumentalities and work engaging parts of the machine;

Figure 3 is a left hand side elevational view showing in part an arrangement of parts for causing release of the thread lock of the machine upon depression of a treadle by the operator;

Figure 4 is a perspective view of the work table of the machine;

Figure 5 is a perspective view of the presser foot of the machine;

Figure 6 is a detail sectional view of a work engaging roll of the machine;

Figure 7 is a perspective view of a type of Sahara sandal for the sewing together of the sole and upper of which the machine shown in Figures 1 to 6 is well adapted, the shoe being shown as it appears immediately after the sewing operation; and

Figure 8 is a cross-sectional view of the shoe shown in Figure 7, taken along the line VIII—VIII of Figure 7.

Referring first to Figures 7 and 8, a type of Sahara sandal, the sewing together of the upper and sole of which the present invention is particularly concerned, comprises a sole 1 having an upstanding rim 3, moulded all around it. The upper edge of the rim 3 is turned outwardly (all around the rim) to form a flange 5 which is substantially parallel to the marginal portion of the sole tread. Conveniently the sole is moulded to the form just mentioned in one operation by moulding between suitably shaped co-operating moulds. The upper of the sandal is conveniently formed of two separate portions, a toe portion 7, and a heel portion 9. The portions 7 and 9 of the upper have each sewn to their lower edges (while the portions 7 and 9 are in the loose state) a bead 11 (best shown in Figure 8) which may consist of a thin leather strip folded around a reinforcing cord. As shown in Figure 7, the two end portions of the bead attached to the toe portion 7 of the upper project for some distance beyond the ends of the portion 7, and when the shoe is assembled, the toe portion 7 and the heel portion 9 of the upper do not meet but the intervening space at each side of the shoe is bridged by the projecting end portion of the bead last referred to, which end portions are sewn to the sole in the same way as the remainder of the bead. The points at which these end portions of the bead on the toe portion 7 of the upper meet the ends of the bead on the heel portion 9 of the upper are shown at 13 in Figure 7. In sewing the sole and upper of the sandal together by a machine, as hereinafter described, the operator will, prior to beginning sewing, say the heel portion 9 of the upper to the sole, make marks on the upper surface of the flange 5 of the sole at the localities 13 to ensure that the heel portion 9 of the upper (which can readily be located to the marks) will be sewn in correct position to the sole. The marks themselves can readily be made in cor-

rect position on the sole by employing a suitably designed template.

The lockstitch sewing machine illustrated in the drawings is particularly adapted for the 5 sewing together of the sole and upper of a scandal such as that just described. This machine, as regards its sewing instrumentalities, is (except as hereinafter described) of the general character of the machine disclosed in the patent 10 to French and Meyer above referred to, to which reference may be made for a full description of parts not herein specifically referred to. The machine comprises a curved hook-needle 15, a needle guide 17, an awl 19, a looper 21, a take-up 23, a work table 25 and a presser foot 27. The machine is equipped with treadle actuated stopping and starting mechanism (not shown) of well known character so that the operator may either, according as he desires, sew a succession 15 of stitches or when proceeding more carefully 20 sew only a single stitch at a time.

The work table 25 of the machine is of usual type, except that, as seen in Figure 4, the front 25 wall 29 is preferably quite thin. This allows a seam to be sewn quite close to the apex of the angle between the flange 5 and the rim 3 when work is presented to the machine, as is indicated in Figure 3.

The presser foot 27 is shown particularly in 30 Figure 5. Its work engaging portion has a substantial degree of extension along the line of feed, and through this portion there is formed a slot 31 extending in the direction of feed and corresponding generally to the slot in the work 35 table 25. The needle and awl operate through the slot 31 and the portion 33 of the presser foot between the forward wall of the slot and the front face of the presser foot acts during sewing as a guard to shield the upper from damage by 40 the needle or awl.

Along the under face of the presser foot with its axis to the rear of the longitudinal median line of the slot 31 there is formed a groove 35 of substantially semi-circular cross-section which 45 extends in the direction of feed from end to end of the work engaging face of the presser foot. As is shown in Figures 1 and 3, this groove serves to engage the bead 11 on the upper to position the bead during sewing. The diameter of the 50 groove is preferably slightly in excess of that of the bead. The lower face of the portion 33 of the presser foot is well below the level of the highest part of the groove 35 so that the portion 33 of the presser foot enters well into the 55 crease between the bead and the upper proper, and holds the upper down towards the flange 5 on the sole at a little distance from the bead, held by the groove. Thus a free passage is ensured for the needle and awl between the bead and upper (somewhat tensioned away from the bead by the portion 33 of the presser foot) so that the 60 needle and awl can penetrate the upper reliably and uniformly at the crease last referred to. The opposite ends of the groove 35 in the presser foot are conveniently rounded off somewhat so that there is a smoothed (and not a sharply angled) 65 entry into and exit from the groove for the bead at the opposite ends of the presser foot.

To assist in supporting the work during sewing, 70 the machine is provided with a horn arrangement, clearly shown in Figure 1. This horn arrangement comprises a bent arm 37 which is secured at its lower end in a bracket 39 by a clamping device comprising a locking handle 41. The arm 75 37 is normally held in fixed position, though this

position is capable of heightwise adjustment. The arm 37 extends upwardly and forwardly, and then upwardly and slightly rearwardly, and passing through a bore in its top end portion is a rod 43 which extends downwardly and rearwardly towards the sewing instrumentalities of the machine and is fixed in adjustable position to the arm 37 by means of a set screw 45. Pivotedly mounted about an approximately vertical axis on the rearward end of the rod 43 is a roll 47. 10 This roll comprises (see Figure 6) a metal hub 49 rotatably mounted on a screw 51. On the hub 49 is carried a solid rubber tire 53 about one inch and a quarter in diameter and some three-eighths of an inch thick. The head of the screw 51 is 15 countersunk into the hub 49 so that a smooth flat lower face is presented by the roll towards the inner face of the sole during sewing. The periphery of the rubber tire 53 is suitably contoured to cooperate, as shown in Figures 1 and 3, with the 20 inner face of the sole rim 3 in holding the outer face of the rim against the front face of the work table 25 as the sole is fed past the sewing point with its flange 5 resting on the upper surface of the work table. The height of the roll 47 is such that 25 its area of contact with the inner surface of the rim 3 of the sole is about on the same level as the area of contact of the front face of the work table 25 with the outer surface of the rim.

It has already been mentioned that the machine 30 may be fitted with a starting and stopping mechanism. Such mechanisms, as ordinarily constructed and arranged, stop an outsole sewing machine in a position in which both the needle and awl are withdrawn from the work, in which the presser foot is locked in engagement with the work, and in which the needle thread lock is closed so as to prevent thread being withdrawn from the thread supply. In order that, at the conclusion of the sewing operation, the work may be readily 40 withdrawn, the illustrated machine is provided with a treadle upon one continued depression of which the presser foot is first unlocked, then it is raised, then after the presser foot has risen slightly, the thread lock is released. This treadle 45 is not itself shown in the drawings but it is connected to a treadle rod 55, depression of the treadle causing depression of the treadle rod which is normally spring pressed upwardly. The arrangement whereby the presser foot 27 is unlocked and then raised by the depression of the treadle rod 55 will first be described. The presser foot 27 is mounted on a lever 57 pivoted on a fixed stud 59 and having a rack 61 secured to its rear end. Also pivoted on the stud 59 is a lever 63 connected with the lever 57 by an arrangement comprising a rod 65 pivoted to the lever 57 and passing through a hole in a lug 67 on the lever 63 and having a compression spring 69 thereon above the lug. The rack 61 is adapted to be engaged by 60 locking pawls 71 which are pivoted to the machine frame at 73 and normally have their teeth pressed towards the rack by springs 75. The lever 63 is connected at its rear end by means of a short pivoted link 75 with the forward end of a cam lever 65 77 which is actuated during each stitch forming cycle of the machine to lift the lever 63 and, through the spring 69 and rod 65 and lever 57, force the presser foot into clamping engagement with the work. The cam lever 77 is lowered in 70 each stitch forming cycle just previously to the work being fed. As the cam lever 77 reaches the limit of its downward movement, a portion 79 of the cam lever engages the tails of the pawls 71 and moves the pawls out of engagement with 75

the rack 61 on the presser-foot lever 57. The downward movement of the lever 77 also acts to relieve the tension on the spring 69, and thereby reduce the tendency of the spring to urge the presser-foot 27 against the work. As has been stated, the illustrated machine is provided with a treadle connected to the treadle rod 55. This treadle rod is pivoted to one arm of a three-armed lever 81 which is pivoted at 83 to the lever 57. The second arm of the three-armed lever is pivotally connected with the pusher 85 which is also connected by means of a pin and slot with the lever 57. When the treadle rod 55 is depressed, the pusher 85 contacts with a pin 87 on one of the pawls 71 and serves to release this pawl from the rack 61 and also to release the other pawl 71 which is engaged by a pin 89 on the pawl 71 carrying the pin 87. When the presser foot is thus unlocked, the third arm of the three-armed lever 81, on further depression of the treadle rod 55, contacts with a face 91 on the lever 57 and thus the lever 57 is then turned clockwise, as seen in Figure 1, to raise the presser foot 27.

The thread coming from the looper 21 passes around a roll at the end of the take-up lever 23, then around a roll at the end of the auxiliary take-up lever 93, then around a roll 95 against which it may be clamped at suitable times by the thread locking lever 97, and then around a roll on the pull off lever 99, from which it passes around a tension device to the supply. The thread locking lever 97 is pivoted on a horizontal shaft 101 and at its rearward end is engaged by a forked member 103 rigidly secured to a horizontal rock shaft 105. Also rigidly secured to the rock shaft 105 is an arm 107, the upper end of which is connected by a yieldable, though stiff, connection to a rod 109 which is actuated from a cam on the cam shaft of the machine.

To actuate the thread locking lever 97 from the treadle rod 55 simultaneously with, or immediately following the lifting of the presser-foot, an arm 111 is rigidly secured to the rock shaft 105 of the locking lever actuating mechanism above described, and is arranged to be engaged by a roll 113 on the upper end of an arm 115 rigidly secured to a rock shaft 117. Also secured to the rock shaft 117 is a forked arm 119 which embraces the treadle rod 55 just below a stop collar 121 secured to the rod 55. Further depression of the rod 55 after the presser foot has been raised slightly brings the stop collar 121 into engagement with the arm 119, and through the connections described, rocks the shaft 105 in a direction to move the thread clamping end of the lever 97 away from the roll 95.

It is believed that the operation of the illustrated machine will have become clear from the foregoing. Briefly to recapitulate, however, the operator to sew such a shoe, as is shown in Figures 7 and 8, will take the sole 1 and position thereon, say the heel portion 9 of the beaded upper (the sole preferably having had, as hereinbefore mentioned, marks made thereon at the localities 13 at which the heel portion 9 of the upper should end). Then he will depress the treadle connected to the treadle rod 55 until the presser foot 27 is raised and, while the parts are in this position, he will present the assembled work (at one end of the heel portion 9 of the upper) to the machine and release the treadle, just mentioned, so that the presser foot 27 is lowered to bring its groove 35 into engagement with the head 11 on the upper. When the work 75 is thus placed in the machine the work table

will position the sole heightwise by its flange. The work table and roll will position the sole between them forwardly and rearwardly by its rim, and the groove in the presser foot will position the bead on the upper heightwise and forwardly and rearwardly. Depression of the treadle which is connected to the stopping and starting mechanism will cause the machine to begin sewing a lockstitch seam, indicated at 123 in Figure 8, to unite the sole and upper. When the heel portion 9 of the upper has been sewn to the sole, the toe portion 7 will thereafter be sewn to the sole in corresponding fashion, the sewing being made to extend along the portions of the bead 11 attached to the toe portion 7 of the upper which extends beyond the toe portion 7 proper up to the localities 13 at which the heel portion 9 of the upper begins. It will, of course, be realized that no last is employed in the shoe during the sewing operation. Conveniently after the sewing operation has been completed, a last may be inserted in the shoe and the bead 11 on the upper subjected to a smoothing or beating operation whereby it is pressed up closely towards the upper to conceal the sewing 123 while the edge 25 of the flange 5 of the sole may be trimmed more closely up to the sewing 123, preferably to a somewhat rounded form.

While the above description of the operation of the machine has been given with relation to 30 the sewing of a sandal in which the upper is composed of two portions it is, of course, to be realized that the machine may be readily used in a similar manner for the sewing of a beaded upper made in one unit to an out-turned flange of a 35 sole such as 1.

During the sewing operation the roll 47 occupies a normal fixed position. There is, however, sufficient yield in the bent arm 37 to allow of the roll 47 being displaced slightly forwardly to 40 enable the operator to insert a sole between the roll and the work table or to remove it from therebetween though, when the sole is in fact between these parts, it is held in position by pressure of the roll 47 against it.

The nature and scope of the invention having been indicated, and an embodiment of the invention having been specifically described, what is claimed is:

1. A shoe sewing machine for sewing the lower beaded edge of an upper to an outturned flange formed on a rim upstanding from the tread portion of the sole having, in combination with the stitch forming devices, a work support shaped and arranged to support the outturned flange on the shoe sole, a presser foot cooperating with the work support to clamp said flange and upper intermittently provided with a groove to receive the bead at the lower edge of the upper, and a horn extending into the shoe and pressing the rim of the sole against the edge of the work support.

2. A shoe sewing machine for sewing the lower beaded edge of an upper to a sole having, in combination with the stitch forming devices 65 including a needle, a work support and a presser foot cooperating with the work support to clamp the upper and sole intermittently, provided with a groove at one side of the needle path to receive the bead at the lower edge of the upper.

3. A shoe sewing machine for sewing the lower edge of an upper to an outturned flange formed on a rim upstanding from the tread portion of the sole having, in combination with the stitch forming devices, a work support shaped and 75

arranged to support the outturned flange of the shoe sole, a presser foot cooperating with the work support to clamp the upper and flange intermittently, and a horn extending into the shoe provided at its inner end with a roll arranged to press the rim of the sole against the edge of the work support.

4. A shoe sewing machine for sewing the lower beaded edge of an upper to a sole having, in combination with the stitch forming devices, a work

support and a presser foot cooperating with the work support to clamp the upper and sole intermittently, said presser foot being provided with a needle slot and with a portion at one side of the needle slot provided with a groove to receive the bead at the lower edge of the upper, and with a portion on the other side of the slot to engage the upper inside of the bead.

OTTO F. HOPPE. 10
